UNITED STATES PATENT OFFICE

HERBERT M. REEVES, OF IRENTON, OHIO, ASSIGNOR TO CONTINENTAL STOVE CORPORATION, OF IRENTON, OHIO

DESIGN FOR STOVE

Application filed October 7, 1930. Serial No. 37,163. Term of patent 7 years.

To all whom it may concern:

Be it known that I, HERBERT M. REEVES, a citizen of the United States, residing at Ironton, in the county of Lawrence and State of Ohio, have invented a new, original, and ornamental Design for Stoves, of which the following is a specification, reference being had to the accompanying drawing, forming part thereof.

The figure is a perspective view of a stove showing my new design.

I claim:
The ornamental design for a stove, as shown.

HERBERT M. REEVES.
